UNITED STATES PATENT OFFICE.

VALENTINE G. BARNEY, OF CHARLES CITY, IOWA.

STONE-SAWING MACHINE.

SPECIFICATION forming part of Letters Patent No. 377,660, dated February 7, 1888.

Application filed June 3, 1886. Serial No. 204,060. (No model.)

To all whom it may concern:

Be it known that I, VALENTINE G. BARNEY, a citizen of the United States, residing at Charles City, in the county of Floyd and State of Iowa, have invented certain new and useful Improvements in Stone-Sawing Machines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation 15 of an elevation, partly in section, of the complete machine. Fig. 2 is an enlarged detail section of the pump and tank. Fig. 3 is a modification.

This invention relates to improvements in 20 stone-sawing mechanism, the main objects being to feed the necessary sand and water automatically to the saws, and to automatically separate the used and worn sand from the new and sharp sand.

25 The invention consists in the construction and novel arrangement of parts hereinafter described, illustrated in the drawings, and pointed out in the claims.

Referring by letter to the accompanying 30 drawings, A designates the frame of the machine, upon which the gang-frame A', holding the gang of saws a a, is reciprocated by a pitman, a', in the usual manner, the block of stone that is operated upon being supported 35 on the main frame over the pit or tank a' at the lower part of said frame.

B is a rotary pump, the wheel or piston B' of which is so geared or connected to its motor as to run very rapidly. The wheel B' is 40 made, preferably, to fit loosely in its casing, so that the water is made to flow, principally, by the rapid motion of the wheel, as in a propeller, centrifugal or other pump that works on this principle. The said wheel turns on a 45 step, C, secured to the floor of a receiving tank, C', as shown, the step-seat c being secured within the vertical hollow shaft c' of the pump-wheel, preferably at a point above the tank C'.

50 D is a clear-water tank situated at a point above the pump, so that the water will gravitate therefrom, and d is a pipe discharging

from said tank into the open upper end of the vertical hollow shaft c' of the pump-wheel. The step-seat is perforated centrally, so that 55 water will descend through the shaft and said seat to lubricate the step.

d' is a tube branching from a pipe, X, that descends from the pipe D to the sand-box X'. The tube d' communicates at its lower end 60 with the lower orifice of an axial perforation of the step, so that water can descend from the tank and lubricate the step by rising centrally through it to the step-seat.

x is the tube or nozzle through which the 65 sand-box discharges into the receiving tank C'.

E is the discharge-pipe of the pump, rising therefrom, then bending horizontally, and E' is the distributor, consisting of two oppositely-inclined boards situated below the end of the 70 discharge-pipe and secured to the frame of the machine, as shown. The distributor may be of any kind in common use, but preferably has upon its outer surface ripples and gates, preferably similar to those shown in the patent 75 granted to me on the 10th day of February, 1885, and numbered 312,068.

The discharge-tube E is divided in its horizontal portion into an upper and lower branch, e e', respectively. The unworn sand will travel 80 at the lower part of the pipe E, and will consequently enter the lower branch, e', and be thrown out on the distributor E', while the worn sand will pass to the upper branch, e, and be thrown directly out of the machine. 85

H is a pipe connecting the pit a' of the machine to the receiving-tank C', or to the casting of the pump should the tank C' be omitted.

The water descends through the pipe X to the sand-box from the clear-water tank, as seen 90 in Fig. 1, and a branch, d', takes the clear water from the pipe X above the sand-box to lubricate the step from its lower end. The upper branch, e, of the tube E discharges immediately out of the machine. 95

If preferred, the tube E may not be divided as described; but a plate, Z, may be secured to its open end, so as to divide stream issuing thence. The good sand goes in the division below said plate into a trough, z, and thence 100 into the distributor, while the worn sand goes with the upper division into a trough, z', and thence is discharged out of the machine.

I am aware of Patent No. 321,293, granted

since my patent above referred to, in which mechanism is employed for feeding sand and water in connection with stone sawing and rubbing machines.

5 In the application of Valentine G. Barney and R. Lester Barney, filed November 4, 1886, Serial No. 218,001, a machine in many respects similar to that shown in present application is shown; but it has the additional features of 10 the coil-pump, the vertical sand-cleaner, the apparatus for returning the sand into the tank that contains the coil-pump, the stuffing-box, with packing to protect the joint of piping, and the mechanism for raising and lowering 15 the saw-frame. These points are not claimed in present application. The application of Barney and Barney has not the divided tube for separating sharp from worn sand, nor has it the step for the pump lubricated with wa- 20 ter, and such parts have not been claimed therein. As both are stone-sawing machines in which water and sand are fed to the saws, they both necessarily have pumps to raise the mixed sand and water, pipes to convey the 25 same, and distributers to feed the mixture to the saws.

Having described this invention, what I claim, and desire to secure by Letters Patent, is—

30 1. In a stone-sawing machine, the combination of the rotatory pump, the receiving-tank surrounding the same, the discharge-pipe having its horizontal portion divided into the upper and lower branches for the used and un-

used sand, respectively, and means, substantially as described, to distribute the unused sand mixed with water, substantially as specified. 35

2. In a stone sawing machine, the combination of the rotatory pump, the surrounding 40 receiving-tank, the discharge-pipe from the pump, with its horizontal part divided into the upper and lower branches, and the distributer-board situated below the end of the lower branch of the discharge-pipe, substan- 45 tially as specified.

3. The combination of the pump B, having the wheel or piston B', the receiving-tank C, the discharge-tube E, divided into the two branches e e', the distributer, the sand-box G 50 and connecting-pipes, and the pipes H, connecting the pit of the machine with the receiving-tank, substantially as specified.

4. In a stone-sawing machine, the combination of the rotary pump, consisting of the casting B and piston B', the perforated step C, the tube c', having within a bearing for the upper rounded end of the step C, the clear-water tank D, and the pipes X and d', whereby wa- 55 ter is conveyed from said tank to the step C, substantially as specified.

In testimony whereof I affix my signature in presence of two witnesses.

VALENTINE G. BARNEY.
